METAL BOUND BOX

Roy F. McMahan, Louisville, Ky.

Application October 15, 1938, Serial No. 235,129

6 Claims. (Cl. 217—69)

My invention relates to improvements in boxes, and has for its object the provision of an improved metal bound box that can be expeditiously manufactured at a low cost.

My invention particularly relates to boxes, cases, crates or containers for the shipping of goods, which boxes et cetera, are intended to be returned to the shipper when empty and repeatedly re-used.

Such boxes et cetera are necessarily subjected to exceedingly hard usage, accordingly, it is essential that they be constructed strong and durable.

In the present embodiment of my invention, I have illustrated same in connection with the type of box ordinarily employed in the transportation of bottles.

Thus, an important feature of my invention resides in the provision of a construction that permits boxes for commercial use to be made from relatively thin and inexpensive material, and whereby the material constituting the sides, ends and bottom can be rigidly and permanently secured together without the use of dovetail or similar joints, nails, wires, screws or battens.

The essential feature of my invention resides in the provision of a metal binding strap of angled section, which strap has teeth formed from each face thereof and pressed into and through juxtaposed ends, sides and bottoms of the box to provide the sole means of holding and securing the same together.

A further feature of my invention resides in so forming the materials and organizing the instrumentalities for assemblage that the sides and bottom of the container are completely and finally secured at one stroke of a power press and likewise each end of said container is finally secured.

Other features and objects of my invention will be apparent from the following detailed description made in connection with the annexed drawings, and from the appended claims which distinctly point out and define the scope of my invention.

In the annexed drawings:

Figure 1 is a perspective view of a box of the type ordinarily employed for the transportation of bottles, which box is constructed and arranged in accordance with the teachings of the present invention;

Fig. 2 is a partial view of one end of the box as viewed from the bottom;

Fig. 3 is a partial view showing one outer face of the metal binding strap;

Fig. 4 is a partial view showing the other outer face of the metal binding strap;

Fig. 5 is a partial view showing the outer face of the binding strap that lies along side 2 of the box;

Fig. 6 is a partial view showing the outer face of the binding strap that lies along end 4 of the box;

Fig. 7 is an end view of the binding strap showing the corner protecting members 8f and 8g before the same are secured to the corresponding side and end of the box;

Fig. 8 is a partial sectional view of the binding strap showing the construction and relation of the short teeth 10 that are pressed through the relatively thin side members of the box, and long teeth 9 that are pressed through the relatively thick end members of the box;

Fig. 9 is an enlarged partial sectional view of the binding strap illustrating a long tooth 9 pressed through end member 4 of the box, but not secured thereto;

Fig. 10 is an enlarged partial sectional view of the binding strap illustrating a short tooth 10 pressed through the side member 2 of the box, but not secured thereto;

Fig. 11 is an enlarged partial view of the corner of the box illustrating teeth 9 and 10 pressed through their corresponding box members, and also showing the relation of the corner protecting members 8f and 8g before being secured to the corresponding box members;

Fig. 12 is a partial sectional view taken along lines 12—12 of Fig. 11 showing the shape of the corner protecting member 8f after same is secured to its corresponding box member;

Fig. 13 is a partial sectional view, illustrating in dot dash lines 9t, the relative progressive steps through which a tooth is moved and formed to secure same to a box member;

Fig. 14 is a partial sectional view illustrating the final shape of a tooth in secured relation with its corresponding box member;

Fig. 15 is a partial sectional view taken along lines 15—15 of Fig. 14 showing a reinforcing bead formed in the tooth, when the tooth is moved into secured position with a box member;

Fig. 16 is a partial plan view illustrating the assemblage of the sides and bottom members of the box in flat form prior to being folded up into the form illustrated in Fig. 21;

Fig. 17 is a partial sectional view showing the preferred construction and arrangement of the forming tools employed in assembling the box;

Fig. 18 is an enlarged end view of one of the tooth forming tools;

Fig. 19 is an enlarged partial elevational view of one of the tooth forming tools;

Fig. 20 is an enlarged partial elevational view of one of the tooth forming tools, which illustrates the tooth 10 pressed into and through box member 4 by pressure plate 14, with the tooth forming tool 12 progressed into position for beginning the forming operation on the tooth;

Fig. 21 is a perspective view illustrating the sides and bottom of the box secured to the binding straps and folded into position for receiving and securing the end members 4 and 5 of the box;

Fig. 22 is an elevational view of the end member 4 of the box prior to its assemblage with the complete box.

With reference to Fig. 1 it will be observed that the box is preferably constructed from five pieces of relatively thin timber, or similar material, to form the side members 1 and 2, end members 4 and 5, and bottom member 3. It will also be observed that all of these box members are rigidly and permanently secured together by two metal binding straps 8 of specially constructed angle section.

Each face of these angled binding straps has a series of teeth formed therefrom, which teeth are adapted to be pressed into and through juxtaposed faces of the box members, in a manner hereinafter described, for rigidly and permanently securing the same together without the use of nails, screws, battens, or other independent securing means.

With particular reference to Figs. 1 through 8, 16 and 21, it will be observed that the teeth along each face of the binding strap have a triangular shape and project substantially at right angles to the corresponding face thereof in substantially a flat plane. In this respect particular emphasis is made of the fact that the plane of each tooth is formed to register with the grain of the timber forming the side, end and bottom members of the box. This construction is clearly illustrated in Figs. 1, 2, 16 and 21. The object of this construction is not only to facilitate assemblage, but to provide the least possible fracturing of the fibres of the timbers so as to afford the greatest mechanical strength. This construction further minimizes rejects because of split timbers that would otherwise be encountered by not having the plane of the teeth substantially parallel with the grain of the timbers. This construction further enables the teeth to be pressed into and through the box members with the least possible disturbance to their free projecting positions, thus assuring proper alignment of the teeth with their corresponding forming or clinching tools, hereinafter described.

In arranging the box members prior to being assembled in the form illustrated in Fig. 1, two specially constructed angled binding straps of the required length and gage are provided, each strap having a series of teeth formed from each of its faces and substantially uniformly spaced throughout its length. The particular relation of each tooth one to the other and to the grain of the timber forming the box members is clearly illustrated in Fig. 1.

In assembling the binding straps with the box members, the two straps are laid parallel on the table of a power press and the sides 1, 2 and bottom 3 laid flat-wise upon the free end edges of the teeth on the corresponding faces of the

binding straps. With the use of suitable tools, such as illustrated in Figs. 17 through 20, the aforesaid box members are pressed downwardly so that the upstanding teeth 10 are pressed into and through the box members. Observe Figs. 9, 10, 11, 13 and 20. Each side member 1 and 2 and the bottom member 3 are spaced, and the upright face of each strap is formed with a V gap or mitre adjacent each junction of side and bottom member so that the box members can be subsequently folded to assume the position illustrated in Fig. 21.

Referring now to Figs. 17 and 20 it will be observed that the tool for pressing the teeth 10 into and through the box members, and for subsequently clinching same, comprises a series of forming tools 12 carried by a die block 11, and a pressure plate 14, normally biased away from the die block 11 to the position illustrated in Fig. 17 by suitable springs or rubber blocks disposed between the die block 11 and pressure plate 14.

Thus, it will be apparent that the pressure plate shown in Fig. 17 first contacts the box members 1, 2 and 3, and presses the teeth 10 into and through same by force from the power press transmitted to said plate through springs 12s, which are sufficiently strong to effect penetration. As illustrated in Fig. 20, each forming tool 12 engages its corresponding tooth 10 after the box member is pressed against the inner face of the binding strap.

Particular attention is directed to the shape and construction of each forming tool 12. It will be observed that the end of each tool 12 has a concaved arcuate contour 12b and an arcuate beading rib 12c located centrally of the lower face of the forming tool 12. Note Figs. 18 and 19. Thus, each arcuate beading rib engages the free end of a tooth in its downward movement and progressively rotates on curls the free end in the manner illustrated in Fig. 13 until the final position illustrated in Fig. 14 is reached. Just prior to the tooth reaching its final position, the resistance of the compressed box member increases and exerts sufficient pressure so as to cause a reinforcing bead to be formed in the curled tooth as illustrated in Figs. 14 and 15.

It is very important to observe that my invention contemplates a slight shearing of the fibres of the box timbers adjacent the inner faces of the box members, so that each tooth is independently and simultaneously curled to a position below the inner face of the box members. This construction eliminates objectionable metallic projections within the box that may otherwise injure the hands of those required to handle the box.

Thus, with a single stroke of the power press the side and bottom members of the box are secured to the corresponding faces of the binding straps, and assume a position illustrated in Fig. 21.

In Fig. 21, it will be observed that each end of the binding strap 8 is provided with corner protecting and end securing members 8g. These members are each curled around the edge of the corresponding box member and their free ends driven into the box members. Note Fig. 12 which particularly illustrates the corresponding member 8f. The tools employed, and the method of effecting the securing of the members 8g and 8f is embraced in my earlier filed application Serial Number 70,933; filed March 26, 1936, and entitled "Hanger and method of attaching same," now Patent 2,201,193, issued May 21, 1940.

After the side and bottom members are secured to the binding straps, the side members 1 and 2 are bent upright as illustrated in Fig. 21, and the end members 4 and 5 placed within the partially constructed box, either separately or together, so that when the required pressure is exerted against each end member, the teeth 9 will be pressed into and through the end member and subsequently curled in the manner outlined for teeth 10, thus rigidly securing the end members to the binding strap in juxtaposition with the sides and bottom of the box. It will also be observed that the end protecting members 8f of the binding strap are also simultaneously curled around the upper edge of the end members and driven therein as shown in Fig. 12 and hereinbefore described in connection with members 8g.

In Fig. 19 it will be observed that each forming tool 12 has a flat portion 12a and is secured to the die block 11 by set screws 15.

From the foregoing it will be apparent that I have provided an extremely effective and durable method of permanently securing the side, bottom and end members to the binding straps 8. This method of securing must not be confused with conventional bending or riveting operations, which do not assure a solid and permanent connection. In this respect particular emphasis is made of the fact that my method of securing assures that the box members are solidly and rigidly secured to the binding straps. Obviously, variations in the thickness of the box members are to be expected, but because of the method of curling the teeth 9 and 10 with the box members, the same positive securing action is provided, even when wide variations are encountered. Further, my curling action is distinct from the conventional riveting operation, in that the upright portion of the tooth passing through the box member retains a taut condition as the free end is curled and pressed into the box member. Obviously, in riveting, the upright portion between the bent free end and base is likewise irregularly bent, which renders it practically impossible to effect a permanent and rigid construction. It is of equal importance to observe that the small diameter forming tool 12 in shearing the fibres of the inner face of the box member adjacent the clinched tooth and binding strap contributes materially to the solid construction of my box.

In summary it is pointed out that the making of a box according to the teachings of my invention consists of providing suitable end, side and bottom box members, which members require no special pre-cutting, forming or jointing. With these members at hand, angled binding straps are formed as illustrated in the annexed drawings, each strap having a plurality of teeth formed in each face in a manner so that each tooth will penetrate its corresponding box member substantially parallel with the grain of the material forming the members.

While the binding straps are in their horizontally extended positions the sides and bottom members are secured thereto by pressing the teeth of the straps into and through the box members and then progressively and simultaneously curling each tooth into clinching relation with its corresponding box member. Then folding the sides into an upright position and securing each end member to its co-related or corresponding binding strap in the same manner in which the sides etc. were secured thereto by means of a separate set of instrumentalities built

on the same principle, thus producing a finished box of durable and solid construction.

It is important to observe that the teeth formed from each face of the binding straps are comparatively close together, and that they are formed away from the horizontal edges of the binding straps. This construction is important, as it assures the holding down of both horizontal edges of each strap tightly against the box, therefore preventing these straps from catching on other boxes. The forming of the teeth away from the horizontal edge also contributes to this important consideration as this leaves each horizontal edge smooth and free from serrated edges that are otherwise provided when the teeth or fastening pieces are struck from the metal along the horizontal edges.

Having thus described my invention, I claim:

1. A box having securing means consisting of a pair of longitudinal "side, bottom, end and corner," metal binding-straps of angular formation, one face of each strap having a plurality of fastening teeth struck from the metal and integral with the said one face of each strap, said fastening teeth of each strap extending into and through the respective sides and bottom of the box and having their free end portions arched longitudinally thereof and curled into the respective inside surfaces of the same, so as to fasten the said sides and bottom together; the other face of each strap also having a plurality of fastening teeth struck from the metal and integral with the said other face of each strap, the latter said teeth of each strap extending into and through the conjoining end of the box and having their free end portions arched longitudinally thereof and curled into the respective inside surfaces thereof, so as to fasten the ends of the box to the sides and bottom, the arched teeth thus forming the sole means for securing the sides, bottom and ends together; and a concave corrugation struck transversely in the arched end of each tooth for securing the same to its curled condition.

2. In a metal-bound box, a metal binding-strap engaging one face of the respective sections of the box and having a plurality of teeth struck therefrom and integral therewith, each tooth extending through its respective box section, and having a free-end portion arched longitudinally throughout the length thereof and curled into the respective box section to clench the same thereto; and a concave corrugation struck transversely in the arched free end portion of each tooth, for securing the same in its clenched condition.

3. In a metal-bound box, a metal binding-strap engaging one face of the respective sections of the box and having a plurality of teeth struck therefrom and integral therewith, each tooth having a flat shank extending through its respective box section and a free-end portion extending beyond the opposite face thereof, the free-end portion of each tooth being folded against its respective box section and arched longitudinally throughout its length so that the end edge thereof is curled into the respective box section; and a concave reinforcing head extending longitudinally throughout the length of the arched free-end portion of each tooth for securing the same in its folded position against the opposite face of the respective box section.

4. In a metal-bound box, a metal binding-strap engaging one face of the respective sections of the box and having a plurality of teeth

struck therefrom and integral therewith, each tooth having a flat shank extending through its respective box section and a free end portion extending beyond the opposite face thereof, the free-end portion of each tooth being folded against the opposite face of the respective box section and arched longitudinally throughout its length so that the end edge thereof is curled into the respective box section; and a corrugation extending longitudinally throughout the length of the arched free-end portion of each tooth for securing the same in its folded position against the opposite face of the respective box section.

5. In a metal-bound box, a metal binding-strap engaging one face of each of the respective sections of the box and having a plurality of teeth struck therefrom and integral therewith, each tooth having a flat shank extending through its respective box section, and a free-end portion folded against the opposite face of the said respective box section and arched longitudinally throughout the length thereof so that the end edge of the tooth is curled into the said

opposite face of the respective box section; and reinforcing means extending longitudinally throughout the arched free-end portion of each tooth for securing the same in its folded position against the opposite face of the respective box section.

6. In a metal-bound box, a metal binding-strap engaging one face of each of the respective sections of the box and having a plurality of teeth struck therefrom and integral therewith, each tooth having a flat shank extending through its respective box section, and a free-end portion folded against the opposite face of the respective box section and arched longitudinally throughout the length thereof so that the end edge of the tooth is curled into the respective box section; and reinforcing means formed in the arched free-end portion of each tooth for securing the same in its folded position against the opposite face of the respective box section.

ROY F. McMAHAN.
